UNITED STATES PATENT OFFICE.

DAVID PERRY COOPER, OF STRUTHERS, OHIO.

TROUSERS-STRETCHER.

SPECIFICATION forming part of Letters Patent No. 779,350, dated January 3, 1905.

Application filed August 17, 1904. Serial No. 221,098.

To all whom it may concern:

Be it known that I, DAVID PERRY COOPER, a citizen of the United States, and a resident of Struthers, in the county of Mahoning and State 5 of Ohio, have invented a new and Improved Trousers-Stretcher, of which the following is a full, clear, and exact description.

This invention relates to trousers-stretchers or hangers, and especially to that class of these 10 devices which comprises clamps which attach securely to the garments and are forced apart by an extensible rod.

The object of the invention is to provide a simple device of this kind with improved 15 means for locking the extensible rod in an extended position. A further object has been to produce a device the parts of which are adapted to fold neatly and compactly.

The invention consists in the construction 20 and combination of parts to be more fully described, and definitely set forth in the claims.

Reference is to be had to the accompanying drawings, which form a part of this claim, in which drawings like characters of reference 25 indicate like parts in the several views, and in which—

Figure 1 is a side elevation of the device, representing the same as being applied to a pair of trousers, the extensible rod referred 30 to above being represented in its unextended condition. Fig. 2 is a side elevation similar to Fig. 1, but representing the stretcher in operation with the extensible rod in its extended condition. Fig. 3 is a longitudinal section through one of the clamps, the same being broken away, this view being upon an enlarged scale. Fig. 4 is a side elevation of a portion of the extensible rod upon an enlarged scale. and Fig. 5 is a side elevation representing the 40 parts of the device unfolded and grouped together.

Referring more particularly to the parts, 1 and 2 represent a pair of clamps, the former of which is adapted to be applied to the lower 45 portion of the trousers 3, while the clamp 2 has greater length and is adapted to be applied at a suitable point, such as that indicated. In their construction these clamps comprise flat bars 4, preferably of wood and provided with 50 bolts 5, passing through openings at their ex-

tremities, as shown. These bolts project as indicated and are threaded for the attachment of wing-nuts 6, passing, as shown, through slots 7 and 8, adapted to receive them, the said slots being formed in an opposing bar 9, as will 55 be readily understood. As shown, the slot 7 is preferably wholly within the bar 9, while the slot 8 extends to the end face thereof. The clamps 1 and 2 are substantially similar in construction; but the clamp 1 is preferably 60 provided with a cord 10 to facilitate the hanging of the trousers, as indicated.

In the adjacent edges of the bars 4 round sockets 11 are formed, and these sockets are adapted to receive the extremities of an extensible rod 12. This rod is formed of sections 13 and 14, which normally make a loose running engagement with each other at the point 15, as shown. To describe this connection at the point 15 more in detail, it should 65 be stated that the inner extremities of the sections 13 and 14 overlap or telescope, as shown in Fig. 4. The extension 13 is formed at its extremity into an eye 16, disposed in a plane substantially at right angles to the axis 70 of the rod, and a similar eye 17 is formed upon the extremity of the extension 14. The extension 13 passes freely through the eye 17, and likewise the extension 14 passes freely through the eye 16, from which arrangement 75 the rod-sections may be extended or telescoped upon each other. The portion of the rod section or extension 13 which lies between the eyes 16 and 17 is formed with an offset, preferably 80 consisting of an enlarged loop 18 disposed laterally in a plane substantially parallel to the axis of the rod. Also the portion of the rod extension 14 which lies between the eyes 16 and 17 is offset to form a loop 19, which is substantially similar to the loop 18, 85 but of reduced dimensions, as will appear.

Referring specially to Fig. 4, it will be seen that the body of the loop 18 forms an acute angle at the point 20, where the straight extension 21 of the rod 13 passes toward the 90 eye 16. From this construction it should now readily appear that by holding the rod extensions 13 and 14 so that the loops 18 and 19 extend in different directions the sections of the rod may be readily extended or telescoped 95 100.

without the loops engaging with each other. However, it should be also apparent that by disposing the loops in a plane substantially at right angles to each other the body of the loop 5 19 may be made to engage the loop 18. Upon this fact depends the operation of the device. On bringing the loops into engagement the loop 19 preferably seats itself in the angle referred to at the point 20.

10 In applying the device the bars 9 should be detached at the extremities having the slot 8, so as to enable the same to be swung down into some such position as that in which they are shown in dotted lines in Fig. 1, enabling 15 the trousers to be received upon the inner faces of the bars 4. The bars 9 would then be applied, as will be readily understood, in order to clamp the same upon the trousers. Before attaching the clamps the extremities of the 20 extensible rod 12 will be received in the sockets 11, and the clamps would be disposed at such a distance apart that the loop 18 will be removed a slight distance below the loop 19, as indicated in Fig. 1. When the parts have 25 been arranged in this manner, the loop 18 will be seized and forced in a direction to extend the rod, moving the same until it has passed the loop 19, whereupon the loop 18 will be rotated laterally upon the axis of the extension 30 13, bringing about the engagement of the loops at the point 20, as described above. In this manner the extensions are securely locked against a relative longitudinal movement, pressing the clamps apart with sufficient force 35 to stretch and crease the trousers, as will be readily understood.

The construction described for the extensible rod 12 adapts the same admirably for being folded for the purpose of packing the same 40 into a box. When in this folded condition, the sections of the rod will assume substantially the relation in which they are shown in Fig. 5, the eye of each rod lying adjacent to the extremity of its mate.

45 It should now appear that the device is very

simple in construction and easily applied, and by reason of the small space which it occupies when not in use it should be especially useful as an adjunct for traveler's toilet equipment.

Having thus described my invention, I claim 50 as new and desire to secure by Letters Patent—

1. In a device of the class described, in combination, a pair of clamps adapted to attach to a garment, an extensible rod having telescoping extensions formed with eyes guiding said 55 extensions one upon the other, and interlocking means carried by said extensions between said eyes.

2. In a device of the class described, the combination of oppositely-disposed clamps, an extensible rod disposed between the same and comprising telescoping extensions, said extensions 60 comprising guiding-eyes and having loops which may engage to lock said extensions against longitudinal movement. 65

3. In a device of the class described, the combination of a pair of clamps adapted to engage a garment, an extensible rod disposed between the same and having guiding-eyes at the engaging extremities thereof, said extensions 70 further having offsets between said eyes which may engage, to maintain said extensible rod in an extended position.

4. In a device of the class described, the combination of a pair of oppositely-disposed 75 clamps, a rod disposed therebetween, and comprising a pair of extensions, the adjacent extremities of said extensions overlapping, and having eyes respectively through which the opposite extension passes, the portions of said 80 extensions between said eyes having laterally-disposed loops adapted to engage.

In testimony whereof I have signed my name to this specification in the presence of two subscribing witnesses.

DAVID PERRY COOPER.
